[57] ABSTRACT

A rotary printer for printing articles advanced step-by-step by a conveyor and thermoformable sheets carried thereby. The printer has a base in support of a carriage and includes structure to reciprocate the carriage relative to the base a predetermined distance lengthwise of the conveyor. The carriage has a rotatable member including at least one arcuate blanket portion that may include sections, one form roll for each color to be printed and for each blanket portion, and an ink distributor for each form roll. Structure is provided to rotate the rotatable member in the same direction in both directions of carriage travel, one direction being the printing direction with the blanket portion or portions engaging the article or articles or the thermoforlable sheet and, in the other direction, each blanket portion being returned to a predetermined starting position and, by then, being at least partially re-inked by rolling engagement with a form roll. Where more than one other form roll is provided for each blanket portion, each blanket portion is re-inked by its rolling engagement therewith so that most of the re-inking is effected in the return stroke. When a blanket portion is a minor arc, the rotatable member is turned at such an increased rate in the inking direction that it is always in its predetermined starting position at the end of the travel of the carriage in its return or inking direction. The printer may be incorporated in a thermoformer.

ROTARY PRINTER FOR USE IN CONJUNCTION WITH AN INDEXED CONVEYOR

This application is a continuation-in-part of Ser. No. 192,190, filed Oct. 26, 1971, now abandoned.

BACKGROUND OF THE INVENTION

In the production of many articles, it is desirable that they be printed, often with a plurality of colors, while they are being conveyed on an indexed conveyor.

As an example of the problem with which the invention is concerned, various articles can be produced from foamed plastic sheets at high rates using thermoformers having heating, forming and blanking stations and step-by-step conveying means for advancing the sheet material from station-to-station. As shown in U.S. Pat. No. 3,504,074, such thermoformers may be provided with printing stations utilizing printing means of the letter press type to print the articles before the blanking station is reached.

The use of that type of printing means has not been entirely satisfactory in a number of respects. Multiple units are required when different colors are to be printed and their operation is relatively slow. In addition, the desired quality of printing is not always attained due to such factors as that letter presses are essentially limited to character printing and that the thickness of the material in the area to be printed may vary slightly and thus affect the quality of the printing even though such variations are of no consequence when considering the appearance or functioning of the articles.

In addition, articles are also formed from thermoformable sheets of plastic that are sufficiently inert to avoid such problems as shrinkage that are encountered in thermoforming articles from foamed plastic sheets. One such plastic, by way of example, and not by way of limitation, is high impact polystyrene. The present practice is to print such materials as a separate operation with the rolls of printed materials being transferred to the thermoformer to be fed therethrough thus to enable the sides of containers and their covers to be printed which is not possible if their printing is effected after the articles are formed in the sheets.

THE PRESENT INVENTION

The general objective of the present invention is to provide rotary printers that can be used in conjunction with an indexed conveyor that positively advances articles or sheet materials into a predetermined position and that are adapted to print different colors simultaneously without imposing limitations on dwell periods and with a higher quality of printing resulting than has hitherto been obtainable.

The above objective is attained by providing a carriage with a rotatable member having at least one arcuate blanket portion of greater radial extent than the remainder of that member, at least one form roll for each blanket portion and tangent with its path, means to deliver ink to each form roll, and a drive for each form roll and the ink delivering means and connected to the rotatable member. The carriage is mounted over the conveyor and is provided with means to reciprocate it through a predetermined stroke. In one direction of the travel of the carriage and during a dwell, the arcuate blanket portion or portions roll against the surface of the sheet material or its article or articles formed

therein that are to be printed and in the other direction of the carriage travel, but not necessarily during a dwell, the blanket portion or portions are returned to a predetermined starting position above the sheet material and out of the path of the articles and, by then, at least partially re-inked by rolling engagement with the appropriate form roll or rolls. The rotatable member is rotated as an incident of its reciprocation. Unless an arcuate blanket portion is 180° in extent, or if its direction of rotation is reversed during the reset travel of the carriage, the rate of rotation of the blanket portion in the reset travel of the carriage is sufficiently increased to ensure that said arcuate blanket portion is in said predetermined starting position for printing at the beginning of each dwell.

A PREFERRED EMBODIMENT OF THE INVENTION

In the accompanying drawings illustrating preferred embodiments of the invention:

FIG. 1 is a side view of apparatus incorporating a rotary printer in accordance with the invention;

FIG. 2 is a side view of the printing station and the printer;

FIG. 3 is a partly sectioned view of the printer taken from its forward end but with the form rolls and ink distributors removed;

FIG. 4 is a plan view of the base of the printer;

FIG. 5 is a fragmentary side view of the base of the printer showing the vertically reciprocable rack frame and the carriage gears;

FIG. 6 is a section taken approximately along the indicated lines 6—6 of FIG. 5;

FIG. 7 is a side view of one of the backing forms and the means operable to raise and lower it;

FIG. 8 is an end view thereof;

FIG. 9 is a section, on an increase in scale, taken approximately along the indicated lines 9—9 of FIG. 8;

FIG. 10 is a schematic view illustrating the position of the arcuate blanking portion in its starting position;

FIG. 11 is a like view illustrating the position of the blanking portion in rolling contact with an article;

FIG. 12 is a like view but illustrating the blanket portion at the end of a printing stroke;

FIG. 13 is another similar view but illustrating the inking of the blanket portion during its return;

FIG. 14 is a fragmentary side view of the carriage showing one of the form rolls and the ink distributor therefor with an end wall of the distributor broken away to show the gearing;

FIG. 15 is a like view but with the distributor broken away to show the several rolls;

FIG. 16 is a section taken approximately along the indicated lines 16—16 of FIG. 14;

FIG. 17 is a partly sectioned view of a form roll unit as seen from its rear;

FIG. 18 is a view of an ink distributor as seen from the end opposite to that illustrated by FIG. 14;

FIG. 19 is a partly sectioned top plan view of an ink distributor with the ink fountain removed;

FIG. 20 is a plan view of the index station of the apparatus;

FIG. 21 is a partly sectioned side view of one of the chain locking devices at the index station;

FIG. 22 is a side view of one of the chain grabbing devices of the indexing means;

FIG. 23 is a schematic view of the air circuitry operating the chain grabbers, the chain locks, the reciprocation of the carriage, the rack frame, and the backing members;

FIG. 24 is a schematic view of the electric circuitry;

FIG. 25 is a fragmentary side view of another printer in accordance with the invention;

FIG. 26 is a view, comparable to FIG. 6, showing the rack frame and the gear of the rotatable member which is alternatively engaged by the racks thereof; and

FIG. 27 is a perspective view of a thermoformer in accordance with the invention incorporating a printer on the infeed side of its heating station.

A rotary printer in accordance with the invention is generally indicated at 30 and is shown in FIG. 1 as incorporated, by way of example, in apparatus for producing from a roll of foamed thermoplastic sheet material 31 such articles as egg cartons 32. The sheet material is advanced step-by-step through a heating station 33, a forming station 34, the station represented by the printer 30, the punching station 35 and the blanking station 36 from which the finished cartons are delivered in stacks. The sheet material 31 is shown as of sufficient width so that two transversely aligned cartons 32 are formed therein at each dwell at the forming station.

As the present invention is concerned only with the printing of indexed articles, the apparatus is not herein detailed with reference to the other stations which are fully shown and described in U.S. Pat. No. 3,504,074. As successful printing is dependent on accurate indexing and conveying, the indexing means generally indicated at 37 and in accordance with co-pending application Ser. No. 64,979, now U.S. Pat. No. 3,688,963, is herein shown in considerable detail as are the conveying means which comprise supporting and hold-down conveyors whose chains are generally indicated at 38 and 39, respectively, which grip the margin of the sheet material 31 between them as it is conveyed to and through the article forming station 34 and while the articles are being printed and thereafter, at least until it has sufficiently cooled to avoid warpage of the articles when blanked therefrom. Such indexing and conveying means are shown as examples only of such means and not by way of limitation of the invention.

The apparatus has a base 40 that is common to the several stations and provided with supports, generally indicated at 41, for vertically spaced sprockets 42 about appropriate ones of which the supporting and hold-down conveyor chains are trained. The sprockets 42 are transversely adjustable to accommodate different sheet widths but only those at the outfeed ends of the chains are shown in detail and these are provided with chain tensioning means 43.

The proximate courses of the chains are held in sheet gripping relation intermediate their ends and the intermediate stations by a series of upper and lower pairs of shoes 44, best seen in FIG. 6. The lower shoes are fixed on members 45 while the upper shoes are slidably thereon and are yieldably urged towards the lower shoes by springs 46. As may be seen in FIG. 22, the supporting chains 38 have rollers 38A interconnected by links 38B with the outer links having inturned flanges 38C providing supporting seats for the margins of the sheet material. The holdown chains 39 have rollers 39A interconnected by links 39B having projecting

teeth 39C for positively gripping said margins against the seats 38C. The remote courses of the conveyors are protected by shields 47 to which the members 45 are connected.

The base 40 is shown, see FIG. 20, as having an inner frame 48 provided with end mounts 49 and 50 including seats 51 and 52, respectively, with the distance between the seats defining the maximum step length. The ends of a tubular stem 53A of a piston-cylinder unit 53 are secured by the mounts 49 and 50. The piston-cylinder unit 53 is of the double-acting type and each end of its stem 53A has a conduit secured thereto opening into its cylinder 53B, the conduit 54 for effecting forward indexing of the conveyors and the conduit 55 for effecting the return of the indexing means into its reset position. The conduits 54 and 55 are connected to a suitable source of liquid under pressure by a conventional four way valve (not shown) set in an indexing position by the solenoid 57 and in a return or resetting position by the solenoid 58. See FIG. 24.

The cylinder 53B of the unit 53 has a support 59 connected thereto by carriages 60 supported by tracks 61 mounted on the frame 48 for free travel between the seats 51 and 52 or a stop or stops 62 detachably mounted on the stem 53A and used when the step length is shortened. The support 59 is provided with actuators 63 and 64 arranged to operate limit switches 65 and 66 and 66A, respectively, mounted on the frame 48 and in practice the actuators 63 and 64 are adjustable lengthwise of the support 59.

The support 59 is provided with chain grabbing devices generally indicated at 67, one for the proximate courses of the chains at each side of the conveyors. Each chain grabbing device 67, see FIG. 22, consists of a housing 68 to which the cylinder 69A of a pneumatically operated piston-cylinder unit 69 is attached with its stem 69B secured to a block 70 slidably supported in the housing on vertically spaced rods 71, the block 70 having a pair of complementary cam tracks 72 and 73 in one side. Chain grabbing jaws 74 have cam followers 75, each entrant of an appropriate one of the aforesaid cam tracks. The jaws 74 are confined within a slideway 76, with which the housing 68 is provided, for vertical movement between an open position in which the proximate courses of the conveyor chains are between them but free and a closed position in which said courses are grabbed. It should be here noted that throughout the maximum distance the chain grabbing devices 67 may travel, the shoes 44 are omitted. The units 69 are both connected to a suitable source 77 of air under pressure, see FIG. 23, and controlled by a four way valve 78 that is normally set by a spring 78A to maintain the jaws 74 in their chain-grabbing positions but is shifted by a solenoid 78B, to effect the movement of the jaws 74 into their open, chain-releasing positions.

Each jaw 74 is provided with a series of teeth 79 disposed and dimensioned for entry between the rollers of the chain which it engages. It will be appreciated, that when the jaws 74 are in their operative relationship, their teeth 79 fit snugly between chain rollers to securely lock the proximate courses of the chains to the support 59 when the piston-cylinder unit 53 is actuated to index the support 59 forwardly, in the direction of the arrow in FIG. 20, from its reset position established by the seat 49 or a stop 62 backed thereby until it reaches the other limit of its travel established by the seat 50 at the other end of the frame 48. The term "for-

wardly" as used herein always means toward the out-feed end of the apparatus. As the distance the support 59 can travel is accurately established, the conveyors and the sheet material 31 are also positively advanced for the exact predetermined distance. Each housing 68 is connected to the support 59 by bolts 80 extending through slots 81 extending transversely thereof to enable their position to be adjusted to vary the spacing between them as required by the width of the sheet material 31 being processed.

Chain locking devices, generally indicated at 82, see FIG. 21, are mounted on the sprocket supports 41 for movement therewith when the distance between the conveyor chains is varied. Each chain locking device 82 is located outside the conveyor chains and has a mount 83 provided with a lengthwise channel 84 shown as receiving the chains of the proximate chain courses. The cylinder 85A of a piston-cylinder unit 85 is secured to the mount 83 with its axis in the plane of the sheet 31 and at right angles to the chains. The stem 85B of each unit 85 is connected to a head 86 slidable in a bore 87 intersected by a vertical slot 88 opening through the inner end of the mount 83. The head 86 has grooves 89 receiving the ends of upper and lower bell crank levers 90 pivotally mounted in the slot 88 by pins 91. The slot 88 is intersected by lengthwise vertical slots 92 slidably confining upper and lower locking members 93. Locking members 93 are supported by the other ends of the levers 90 so that they are movable between an inoperative position in which the chains are free into an operative position in which the chains are locked against moving. Each locking member 93 has a series of teeth 94 which like the teeth 79 of the grabbing devices are disposed and dimensioned to fit snugly between the rollers of the engaged chains. The locking devices 82 secure the chains and accordingly the sheet material 31 against movement during dwells at which time the various operations, including printing, may be made on the sheet material 31. The units 85 are connected to the air source 77 by a four way valve 95, set in a locking position by the solenoid 95A and in a chain releasing position by a solenoid 95B. See FIGS. 23 and 24.

The printer 30 has a base generally indicated at 96, see FIGS. 2, 3, and 4, and includes side members 97 interconnected at their ends by ties 98 to provide a frame at each corner of which there is an elevator, generally indicated at 99. Each side member 97 has a pair of spaced posts 100 slidably fitting depending sockets 101 with which a support, generally indicated at 102 is provided. Each elevator 99 includes a depending vertical rod 103, see FIG. 3, that is anchored to the support 102 and includes a worm 104 meshing with a worm gear 105 on a shaft 106 common to the elevators at two ends and operable to move the associated rod 103 axially, in one direction to raise the support 102 and in the other direction to lower it. One side member 97 has a centrally located shaft 107 connected by meshing helical gears in a gear box 108 to a shaft 111. The shaft 107 is adapted to be manually rotated as by means of a detachable crank, not shown. The shaft 111 is the drive shaft of gear boxes 112, one at each end of the frame and of which the shafts 106 are the driven shafts. By these means the support 102 may be raised or lowered with its level always maintained.

The support 102 is provided with laterally spaced lengthwise rods 113 slidably supporting a carriage, gen-

erally indicated at 114. The carriage 114 includes two sides 115 interconnected at one end by a cross rod 116 and at its other end by a member 117 having a head 118 to which is attached the stem 119A of an air-operated, double-acting, piston-cylinder unit, generally indicated at 119 whose cylinder 119B is fixed to a mount 120 on the support 102 adjacent the index station. The cross rod 116 and the member 117 have brackets 121 in support of bearings 122 through which the rods 113 slidably extend. The unit 119 is operated by air from the source 77 under the control of a four way valve 123 normally set by a spring 123A to cause the stem 119A to be retracted effecting forward travel of the carriage 114 but operable by a solenoid 123B to effect the extension of said stem during which travel printing is effected. See FIGS. 2, 23, and 24.

Journalled in and extending through the sides of the carriage 114 is a shaft 124 to which a pair of spaced blanket roll members generally indicated at 125 and the drive gear 126 for the ink distributing means, later to be detailed, are keyed. At one side of the carriage, the shaft 124 is provided with a hand wheel 127 and adjacent its other end, it has a hub 128 to which a clutch hub 129 is slidably splined. See FIG. 6. A large gear 130 and a smaller gear 131 are keyed together and are supported on the end of the shaft 124 by a bushing 132 and are held thereon by a retainer 133. The clutch hub 129 is provided with clutch pins 135 disposed so that when the hub is in a predetermined position relative to the gear 130, each may enter the appropriate one of the clutch sockets 136 with which the larger gear 130 is provided. The carriage sides 115 are also interconnected by tie rods 137 and a central tubular tie rod 138 through which a rod 139 extends with one end connected by a ball and socket joint 140 to a shifting fork 141 pivotally mounted at 142 on one side wall 115 and in operative engagement with the clutch hub 129. The other end of the rod 139 is connected by a ball and socket joint 144 to a manually operated shifting lever 145 pivotally mounted as at 146 on the other carriage side 115 and yieldably held by a spring 147 so that the gears 130 and 131 are normally connected to the shaft 124. In practice, the clutch is disengaged for servicing and while making adjustments.

It will be noted, see FIGS. 2 and 10 – 13, that each blanket roll member 125 in the preferred embodiments of the invention, includes a raised arcuate portion 125A that is shown as 120° in extent, one for each of the two carton covers 32A that are to be printed at each dwell, and that the carriage 114 also supports a series of pairs of form rolls, one form roll for each blanket roll portion 125A and tangent to its path. The pairs of form rolls are generally indicated at 148, 149, and 150, but as they are identical only the form rolls 150 and their supporting structure are detailed. See FIGS. 14 – 17. Each pair of form rolls is supported by a shaft 151 mounted on a shaft 152 by ball bearing units 153 with each shaft 151 having a gear 154 in mesh with the drive gear 126.

Each shaft 152 is supported in bushings 155 mounted in brackets 156 which are also interconnected by eccentric shafts 157 and 158. The ends 152A of the shafts 152 are eccentric as may be seen in FIG. 16, and are supported by links 159 detachably connected to the carriage side walls 115 by pivots 160. The shafts 152 are also supported by links 161 connected to the side walls 115 by pivots 162. An arm 163 is fast on the ex-

tremity of each of the shafts 152 and includes a handle, generally indicated at 164, enabling the arm 163 to be easily turned and because of the eccentric end portions 152A, such turning moves the associated pair of form rolls thereon towards or away from the blanket portions 125A. Each handle 164, see FIG. 16, includes a tubular socket 165 slidably supporting a plunger 166 within it with a spring 167 yieldably urging the plunger tip into engagement with a selected one of an arcuate series of recesses 168. The plunger 166 extends through the closed end of the socket 165 and is pinned to a sleeve 169 dimensioned to fit freely over the socket 165 thus to enable the plunger 166 to be manually retracted to free the arm 163 to permit the aforesaid adjustment.

The function of the shafts 157 and 158 is to support the ink distributor units of which there are shown, one for each form roll and for an ink of particular color. The three units are generally indicated at 170, 171, and 172. These are identical as to their construction and, accordingly, only the unit 170 will be detailed.

The distributor 170 includes a pair of side walls 173 interconnected by spacers 174 with a gear housing 175 connected to one side wall. The front upper edge of each side wall 173 is formed with a downwardly opening hook 176 dimensioned to be caught over the eccentric shaft 157. Upwardly opening latches 177 dimensioned to catch an eccentric shaft 158 are mounted on a shaft 178 supported by the side walls 173 adjacent the bottom end of their front edges. Each shaft 178 is provided with a handle 179 enabling the shaft to be turned against the action of a spring 178A.

It has been noted that the shafts 157 and 158 are eccentric and as the distributor units are hung thereon, their relation to the form rolls is variable by turning either one or both of the shafts. In practice, it is usually unnecessary to turn the shafts 157 after initial adjustments. As the shafts 158 may require adjustment from time to time, each is provided with an arm 180 provided with a handle generally indicated at 181. Each handle 181 may be identical to the handles 164 and they are, for that reason, not detailed but each includes a retractable plunger by which its tip may be released for re-engagement with the selected one of the arcuate series of recesses 182.

The side walls of each distributor unit support a shaft 183 provided with an ink roll 184 fitting the outlet of a conventional detachable ink fountain 185 and receiving ink therefrom. The shaft 183 of each ink distributor unit is provided with a gear 186 in the housing 174 connected thereto by a one way clutch 187 and with a knob 188 connected to its end enabling the operator to turn the ink roll shaft 183 freely in one direction to ink it at the start-up. The side walls 173 of each unit also support a transverse shaft 189 loosely supporting a pair of arms 190 holding a shaft 191 having ductor rolls 192, see FIGS. 15 and 19. The shaft 189 has a central arm 189A connected to the arms 190 by a rod 190A and urged towards the ink roll 184 by a spring 189B. The outer end of one shaft 189 is provided with an arm 193. The ink roll shaft 183 also has a cam 194 engageable with the arm 193 and operable to seize the ductor rolls 192 out of engagement with the ink rolls 184 and into engagement with oscillating rolls 196. It should be noted that each cam 194 includes an adjustable portion 194A to enable the interval of engagement of the ductor rolls 192 and the ink rolls 184 to be adjusted

thereby to vary the amount of ink transferred from one to the other.

The oscillating rolls 196 of each unit are mounted on a sleeve 197 fitting a shaft 198 whose ends are within 5 transversely disposed upwardly opening slots 199 in the side walls enabling the rolls 196 to be seated by gravity against distributor rolls 200 fixed on a shaft 201 and provided with a gear 202 and meshing with the form roll gear 154. Oscillating rolls 203 mounted on a sleeve 10 204 on a shaft 205 whose ends are within transversely aligned upwardly opening slots 206 in the side walls so that the rolls 203 may also be seated by gravity against the distributor rolls 200. The rolls 196 and 203 are reciprocated axially by the like means so that only the reciprocating means for the rolls 196 are shown, see FIG. 15 18. The shaft 198 has an endless track 207 in the form of right and left hand helices with the sleeve 197 including a follower 208 within the track 207 so that as the rolls 196 turn, they reciprocate axially a short distance. As the rolls 196 and 203 are in contact with the distributor rolls 200 they are rotated thereby.

The gear train between the distributor roll shaft 201 and the ink roll gear 186 may be seen in FIG. 14 and includes a smaller gear 209 on the shaft 201 and in 25 mesh with an idler 211. The idler 211 meshes with a gear 212 rotatable with which is a smaller gear 213 driving an idler 214 which in turn, meshes with the ink roll gear 186. The coaxial gears 212 and 213 and the gear 214 are supported by a bracket 215 mounted within the gear box 175.

From the foregoing it will be apparent that when the carriage shaft is rotated, the form rolls are turned and that the relationship between them and the blanket rolls may be adjusted to ensure their most effective engagement. It will also be apparent that the distributor units are adjustably positioned to ensure the desired contact between the distributor rolls and the form rolls and that the ink rolls and distributor rolls are rotated thereby. It will also be apparent that the form rolls contact only the raised portion 125A of the blanket roll.

It will be noted that, see FIGS. 5 and 6, the support 45 102 is provided with an air-operated, double-acting, piston-cylinder unit 216 whose stem 216A is connected to a frame 217 slidably supported by vertical posts 218 mounted on the support 102. The frame 217 includes an upper lengthwise rack 219 overlying the gear 131 of the carriage shaft 124 and a lower lengthwise rack 220 underlying the carriage shaft gear 130. With this arrangement, the blanket roll members 125 are rotated in the same direction in either direction of the carriage travel by bringing the rack 220 into engagement with the gear 130 when the carriage 114 travels in one direction and bringing the rack 219 in mesh with the gear 131 when the carriage travels in the opposite direction. The racks 219 and 220 are vertically spaced so that on short travel of the stem 216A of the unit 216 in either direction, one gear is brought into engagement with its rack and the other gear disengaged from the other rack. The support 102 has a frame 221 supporting vertically spaced limit switches 222 and 223 and the frame 50 55 60 65 70 75 80 85 90 95 100 105 110 115 120 125 130 135 140 145 150 155 160 165 170 175 180 9345 9350 9355 9360 936

225B which, when energized, shifts it to effect the raised position of the rack frame. It will also be noted that the support 102 is provided with limit switches 226 and 227 with the carriage 114 provided with actuators 228 and 229 with the switch 226 engaged and operated at the forward limit of the carriage's travel by the actuator 228 and the switch 227 engaged by the actuator 229 and operated at its other limit of travel.

In operation, see FIGS. 10 - 13, printing is effected when the piston-cylinder unit 119 is operated to retract its stem to move the carriage 114 forwardly with the gear 130 then being in mesh with the rack 220. The blanket roll portions 125A were inked when the stem 119A was extended, the gear 131 then being in mesh with the rack 219. As the blanket roll portions 125A are, in the disclosed embodiment of the invention, only about 120° in extent, the shaft 124 is rotated twice as fast during the inking stroke as during the printing stroke with the desired ratio established by the difference in diameter of the gears 130 and 131. By these means, the blanket roll portions 125A, when the carriage 114 is in its reset position, are always in a predetermined starting position to print, during a dwell, carton covers 32A presented to them as the carriage moves forwardly towards the index station 37. When the carriage is again returned at the end of the printing stroke into its reset position, there is no further contact of the blanket portions 125A with the carton covers and the blanket portions are successively in contact with the several form rolls but desirably out of contact therewith when the carriage 114 is fully advanced.

In order for printing to be most effective, particularly with a flexible sheet held only at its margins, it is necessary that the carton covers 32A be firmly supported while engaged by the blanket roll portions 125A. For that reason, see FIGS. 7 - 9, the base 40 is provided with a pair of air-operated, double-acting, piston-cylinder units 230 each with its cylinder 230A connected by a vertical adjusting screw 231 to a mount, generally indicated at 232, fixed on the base 40, each under the position occupied by a carton cover at the printing station during a dwell. The stem 230B of each unit 230 includes a head 233 on which is secured a backing form 234 shaped and dimensioned to fit within a carton cover 32A when the units 230 are actuated to raise their heads 233. In practice, each mount 232 includes vertical slideways 235 for the ribs 236 with which the heads 233 are provided thus to prevent misalignment of the backing forms 234 and carton covers. Each unit 230 is under the control of a valve 237 normally set by its spring 237A to lower the backing forms and provided with a solenoid 237B which, when energized, shifts the valve 237 to effect the raised position of the backing forms.

While the upper limit of each head 233 is readily varied by means of its adjusting screws 231, horizontal adjustments are also provided for by as the mounts 232 include a fixed bottom member 238, a plate 239 having a keyway 240 slidably receiving a key 241 carried by the bottom member 238. The plate 239 extends beyond the ends of the bottom member 238 and has depending blocks 239A through which screws 242 are threaded to engage with sides of the member 232A which is common to both units 230 thus to permit the plate 239 to be shifted lengthwise relative to the printing station. The adjusting screw 231 is carried by a plate 243 of which the slideways 235 are parts and which has a key-

way or keyways 244 disposed at right angles to the keyway 240 and receiving keys 245 carried by the plate 239. Blocks 246, one fastened to one end of the plate 239 and the other fastened to the corresponding end of the plate 243 are provided with adjusting screws 247 and the plate 243 has slots 248 freely accommodating screws 249 which are threaded in the plate 239 and are operable to securely clamp the plates 239 and 243 together.

10 It will be appreciated that the printing operation must be completed during a dwell but because, after the portions 125A have completed their rolling contact with the carton covers 32A, there being no further contact of the printing rolls therewith, the inking step may be 15 wholly or partly performed during a conveyor step. It is essential, however, that the leading edge of each blanket roll portion 125A be in a precise predetermined position at the start of a dwell and it is also provided that the backing forms 234 be operatively positioned relative to the carton covers when the carriage 114 is at its forward limit of travel.

15 As the invention is concerned only with the operation of the printer at a dwell, only that part of control circuitry is shown that is related to the indexing and printing means.

20 A generally indicated circuit 250 includes a control switch 251 and has a series of parallel leads of which the lead 252 includes the normally closed switch 253A of the timer 253, a branch lead 254 and a series of 25 switches generally indicated at 255 closed when operations at the article-forming station 34, the punching station 35 and the blanking station 36 have been completed, the normally open limit switch 65 which is closed when the support 59 is in its reset position, and the relay 256. The branch lead 254 includes the normally closed switch 258A of the relay 258 and the solenoid 95B effecting the chain-releasing positions of the locking device 82. The lead 259 has the normally open switch 256B of the relay 256, the normally closed switch 258B of the relay 258 and the relay 256.

25 It will thus be apparent that if the operations at the stations have been completed, the time controlled dwell terminated and the support 59 in its reset position, the circuit to the timer 253 is open as will presently be described, the lead 252 is closed to energize the relay 256 with its switch 256B now closed so that the lead 259 serves as a holding circuit therefor.

30 The lead 260 has parallel leads 261 and 262 with the branch lead 261 having the normally open switch 256C of the relay 256 and the solenoid 57 by which the valve in control of the conduits 54 and 55 is set to cause indexing. The lead 262 is provided with the normally closed switch 256D of the relay 256 and the solenoid 58 which, when energized, effects resetting of the support 59.

35 When the relay 256 is energized the relay switch 256C is closed with the solenoid 57 energized and the relay switch 256D is open. The normal status of the grabbing devices 67 is that the jaws 74 are in their closed, chain-grabbing positions. The support 59 now moves forwardly carrying the conveyor chains with it until its other limit of its travel is reached.

40 The lead 263 has the limit switch 66 closed when the support 59 reaches said other limit of travel and the relay 258 which is now operable to open the switch 258A in the holding circuit for the relay 256. The lead 264 has the normally open switch 258C of the relay

258 and the timer 253 so that with the relay 258 energized the timer 253 is started and its switch 253A is then opened. The switch 258B is of the type having a brief, predetermined time delay before it opens. As a consequence, when the relay 258 is energized, its switch 258A is instantly opened while the relay 256 is held energized for an interval delaying reset travel of the support 59.

The lead 265 has the normally open timer switch 253B and the normally closed switch 66A which is opened by the support 57 at the end of a step, and the parallel leads 266, 267, and 268. The lead 266 includes the solenoid 95A which is energized to lock the chains against movement, such locking occurring before the resetting of the indexing means because of the time delay feature of the switch 258B. The lead 267 includes the solenoid 78B which is now energized to cause the grabbing devices to release the chains. The lead 268 includes a relay 269 operable to close its normally open switch 269A in the holding lead 270. The lead 271 includes the normally open switch 253B of the timer 253 thus to serve as a holding circuit therefor and for the relay 272 in parallel with the timer 253 and controlling other circuitry to enable operations at other stations to be performed during a dwell. Thus, at the end of a step, the grabbing devices 67 are released and the locking devices 82 operated to lock the chains and the support 59 then returned to its reset position.

At the end of the resulting reset travel of the support 59, the support 59 again closes the limit switch 66 but the relay 256 cannot be again energized until the end of the timed dwell and the series of limit switches 255 in the lead 252 are again closed.

The circuit 275 for the printer 30 includes parallel leads 276, 277, 278, 279, and 280.

The lead 276 is provided with the normally open switch 281A of the relay 281, the normally open switch 258D of the relay 258 closed when the support 59 is in its forward, step-ending position, the normally closed switch 282A of the relay 282 and the relay 283 having a normally open switch 283A in a holding lead 284.

The lead 277 has the normally open switch 272A of the relay 272 closed when the timer 253 is in operation, the manually operated switch 285, the limit switch 223 which is normally open and closed when the rack frame 217 is lowered and the relay 281. The lead 278 is a holding lead for the relay 281 and includes the normally open switch 282B of the relay 282.

The leads 276 and 277 have a connection 286 between the switches 281A and the switch 258D of the lead 276 and the switches 285 and 226 of the lead 277, the connection being common to the holding lead 284 and a lead 287 provided with the normally open switch 288A of the time delay relay 288 and including parallel solenoids, the solenoid 237B of the valve 237 which when energized shifts that valve to effect the raised position of the backing forms 234 and the solenoid 225B of the valve 225 which, when energized operates the unit 216 to raise the rack frame 217 into its position with the rack 220 engaging the gear 130 for the printing stroke of the carriage 114.

In the normal position of the control valves of the printer, they are positioned by their springs so that the stem of the unit 119 is retracted to place the carriage 114 in its forward position, and the backing forms 234 in their lowered or "down" positions, and the rack 219 then meshing with the gear 131.

With the printer in operation, the lead 277 is closed, when the timer 253 starts, to the lead 276 through the connection 286 when the switch 258D is closed as it is when the index support 59 is forward at the start of a dwell. The switch 282A is normally closed so that the relay 283 is energized closing its switches 283B in control of the time delay relay 288 in the lead 280. As a consequence, the switch 288A closes so that the solenoids 237B and 225B are energized resulting in the backing forms 234 being operatively positioned and the gear track frame 117 raised so that the rack 220 and the gear 130 are engaged. When the rack frame is in its lowered position, the normally open switch 223 is closed and the relay 281 is energized closing the relay switch 281B in the lead 279 which includes the switch 222 which is normally opened but closed when the rack frame 217 is raised and the solenoid 123B in control of the unit 119 then energized with the result that the carriage 114 is driven into its reset position. The relay switch 281A is also closed holding the relay 283 and the solenoids 237B and 225B energized.

The lead 279 also includes parallel leads 289 and 290 to the relay 282 with the lead 289 including the normally open limit switch 226 that is closed when the carriage 114 reaches the forward limit of its travel while the lead 290 includes the normally closed limit switch 227 that is open when the carriage 114 is in its reset position at the end of the printing stroke. Thus at the end of the printing stroke of the carriage 114, the relay 282 is de-energized and its switch 282A again closes and its switch 282B opens with the result the relay 281 is energized. When the time delay relay 288 shuts off, the switch 288A opens de-energizing the solenoids 237B and 222B. The switches 272A and 258D are controlled by the appropriate relays of the index circuit. With the solenoids 237B, 225B and 123B de-energized, the carriage 114 returns to its forward position with the rack frame 217 down and the supports 233 in their lowered, inoperative position.

It will be noted that the printing stroke is completed during a dwell but that it is only necessary that the inking stroke be completed before the start of the next dwell.

In the embodiment of the invention previously described, the arc defined by the blanket portions 125A was a minor one. In the embodiment of the invention illustrated by FIGS. 25 and 26, the blanket portions 292 of each blanket roll member 291 is sufficiently close to 180° in extent that the blanket roll members can turn 180° both in the printing and in the return travels of the carriage and are divided into two identical sections 292A and 292B.

In this embodiment it is assumed that a plurality of pairs of articles, in this case two pairs of egg cartons 293, are to be printed at the printing station at each dwell. In this situation, the blanket roll members may be rotated at the same rate during the printing stroke of the carriage 294 and during its return to its reset position so that the blanket roll shaft 295 is provided with but a single gear 296 engaged in the alternate by the vertically spaced racks 297 and 298 of the frame 299 which otherwise is similar to the rack 217. As a printer in accordance with this embodiment of the invention may be otherwise the same as that previously described, it is not further detailed. It should be noted, however, that the preferred arrangement of the form rolls 300, 301, and 302 and their ink distributors 303

is such that when the carriage 294 is returned to its reset position, the blanket portions are not in contact with a form roll. The section 292B is not completely inked during the return travel of the carriage 294 but becomes fully inked by the form roll 302 during the printing stroke.

The sheet material 31 has not been previously defined other than that it is a foamed thermoplastic. One attribute of the invention is that the sheet material may be a foamed plastic or an oriented polystyrene, for examples, as the printing follows the formation of articles in the sheet material and a thermoformer in accordance with U.S. Pat. No. 3,504,074 prevents the physical changes occurring in the sheet as it cools from affecting the exact registry of the articles when they reach the printing station.

Where the sheet material is a thermoplastic of which high impact polystyrene or high density polyethylene are two examples that do not present a problem of shrinkage after being heated and having articles formed therein, the sheet may be printed before the articles are formed therein. As stated earlier, it is the practice, particularly when the sides of containers and covers are to be printed, to print such inert sheet material before it is formed into a roll to be mounted at the infeed end of a thermoformer.

Reference is now made to the thermoformer shown in FIG. 27 as having a printer 30B, which may be and desirably is identical, except as required by its changed position, to the rotary printer 30 or the printer illustrated by FIGS. 25 and 26, said position now being at the infeed side of the heating station 33B. The thermoformer may be and is shown as otherwise in accordance with said U.S. Pat. No. 3,504,074 with its forming and blanking stations indicated generally at 34B and 36B, respectively, and its indexing means may be and desirably are of the type disclosed in aforesaid application Ser. No. 64,979 ensuring precision indexing. As a consequence, the thermoformer of FIG. 27 and its operation including that of its printer 30B is not further detailed other than to note that the unprinted sheet 31B of thermoplastic sheet material is now printed at the infeed end of the thermoformer and is quickly and thoroughly dried as it passes through the heating station 33B. The indexing means precisely advances the printed sheet therefrom into the forming station 34B with the formed articles, including their sides, now bearing the desired printing.

From the foregoing, it will be appreciated that printers in accordance with the invention are well adapted to meet the requirements of printing a wide range of articles as an incident of their production. The use of a carriage with a vertically shiftable rack frame is preferred to the use of a carriage that is shifted vertically relative to the conveyor means or of conveyor means that are shifted vertically relative to the carriage. The use of the vertically shiftable rack frame is also preferred to the use of gear trains provided with gear shifting means and, as in the case of the disclosed embodiments, it is preferred that the blanket roll members always turn in the same direction.

We claim:

1. A rotary printer for use in conjunction with a step-by-step conveyor in printing, during dwells, the upper surfaces of the portions of long lengths of thermoplastic sheet material or of articles formed therein that are exposed during a dwell, said printer comprising a car-

riage, means to reciprocate said carriage through a predetermined stroke over said conveyor from a predetermined starting position, said carriage including a rotatable member provided with an arcuate blanket portion engageable with the surface to be printed and of a radius greater than the remainder of the member, of a width equal to the width of the surface to be printed and of a length equal to the length of the surface of the material to be printed during a dwell, means to rotate said member as an incident of its reciprocation but always in the same direction, said carriage also including at least one form roll tangent with the path of said arcuate portion, means to deliver ink to said form roll, and a drive for said form roll and said ink delivery means connected to said rotatable member, said blanket portion in one direction of carriage travel rolling against the surface to be printed and in the other direction of carriage travel being returned to a said starting position with the blanket portion disposed away from the conveyor for engagement with said form roll to be at least partially inked by rolling engagement therewith when it is at said starting position, and means to initiate the operation of said reciprocating means through a complete stroke at the start of each dwell and effecting at least said one direction of travel during that dwell.

2. The rotary printer of claim 1 in which the blanket portion defines a minor arc and the means rotating the member effects the rotation thereof at a sufficiently higher rate in the return direction of the carriage to place the blanket portion in said starting position at the end of the travel of the carriage in said return direction.

3. The rotary printer of claim 1 in which the printer includes supporting structure, means connecting the carriage to the structure laterally of the conveyor for movement relative thereto through said predetermined stroke and the member rotating means includes gear means rotatable with the rotatable member of the carriage, first and second rack portions extending lengthwise of the path of the carriage, and means to effect relative vertical movement between said racks as a unit and said carriage between limits, said rack portions being disposed for engagement with the gear means in the alternative, one rack portion in one direction of carriage travel at one of said limits and the other rack portion in the other direction of travel at the other of said limits.

4. The rotary printer of claim 3 and a clutch releasable interconnecting the gear means from the rotatable member.

5. The rotary printer of claim 3 in which the gear means includes first and second gears of different sizes, one for each rack portion, the blanket portion defines a minor arc, the smaller gear is in engagement with its rack portion during return travel of the carriage and its size is such as to turn the rotatable member of the carriage at a sufficiently increased rate to ensure that the blanket portion is in said starting position at the end of said return travel.

6. The rotary printer of claim 1 in which the printer includes supporting structure, means connecting the carriage to the structure laterally of the conveyor for movement relative thereto through said predetermined stroke and the member rotating means includes gear means rotatable with the rotatable member of the carriage, a frame mounted on said structure at one side of

the conveyor for vertical movement between two limits, first and second rack portions extending lengthwise of the path of the carriage and connected to said frame, means connected to said frame and operable to reciprocate it between said two limits, said rack portions being disposed relative to said gear means for engagement therewith in the alternative, one rack portion in one direction of carriage travel at one of said limits and the other rack portion in the other direction of carriage travel at the other of said limits.

7. The rotary printer of claim 1 in which the arcuate extent of the blanket portion is such the rotatable member may turn at the same rate in both directions of carriage travel with the blanket portion being in its starting position at the end of the return stroke.

8. The rotary printer of claim 1 in which there are a plurality of form rolls each of which includes means to deliver ink thereto and each including a drive connected to the rotatable member, each form roll tangent with the path of said arcuate blanket portion, the form rolls are spaced from each other and so located that said blanket portion is engaged and completely inked by all of them before returning to said starting position.

9. The rotary printer of claim 1 in which there are a plurality of form rolls each of which includes means to deliver ink thereto and a drive connected to the rotatable member, each form roll tangent to the path of the arcuate blanket portion and the form rolls are spaced from each other and so located that said blanket portion is partially inked by the form rolls during the return of the carriage and the inking of the blanket portion is completed during the printing stroke.

10. The rotary printer of claim 1 in which there are a plurality of form rolls, each including means to deliver ink thereto, and a drive for the form rolls and the inking means connected to the rotatable member, each form roll tangent to the path of the arcuate blanket portion, the blanket portion includes spaced sections and the form rolls are so spaced from each other and arranged that when the arcuate portion is returned to its starting position, the arcuate portion is completely inked except for its trailing section and the line of tangency of a form roll is between the leading and trailing section.

11. The rotary printer of claim 1 in which there are a plurality of form rolls, each including means to deliver ink thereto and a drive connected to the rotatable member, each form roll tangent to the path of the blanket portion, the surface to be printed at each dwell includes a plurality of longitudinally spaced zones to be inked, and the blanket portion includes a like number of appropriately spaced and dimensioned zones, the total arcuate extent of the zones of said blanket portion being such that the entire carriage travel in said one direction is required for the printing of the zones of the material present during a dwell, and the form rolls are so spaced from each other and so arranged that when the blanket portion is returned to said starting position the line of tangency of the last form roll to engage said portion is between two zones.

12. In combination a thermoformer including a heating station, an article forming station, and a blanking station, a conveyor for positively carrying a sheet of a thermoplastic material through said stations in the order named, means to advance said conveyor step-by-step through said stations, a printer adjacent the infeed

end of said conveyor but where it is positively advanced thereby and operable to print the sheet before its passage into the heating chamber, and means to operate said printer during a dwell to print that portion of sheet that is to be formed into an article at said forming station, said printer of the rotary type and includes a carriage, means to reciprocate said carriage through a predetermined stroke over said conveyor, said carriage including a rotatable member provided with an arcuate blanket portion engageable with the surface of the sheet of a radius greater than the remainder of said rotatable member, means to rotate said member as an incident of the reciprocation of said carriage but always in the same direction, said carriage also including at least one form roll tangent with the path of said arcuate portion, means to deliver ink to said form roll, and a drive for said form roll and said ink delivery means connected to said rotatable member, said blanket portion in one direction of carriage travel rolling against the surface of the sheet and in the other direction of carriage travel being returned to a predetermined starting position with the printing portion out of the path of the sheet and, by then, at least partially re-inked by rolling engagement with said form roll, said reciprocating means effecting at least said one direction of carriage travel during each dwell.

13. The combination of claim 12 in which the member rotating means effects the rotation of said rotatable member in said other direction of carriage travel at a sufficiently higher rate to place the blanket portion in said starting position before the next dwell.

14. A rotary printer for use in conjunction with a step-by-step conveyor in printing, during dwells, the upper surfaces of thermoplastic sheet material or of articles formed therein, said printer comprising a carriage, means to reciprocate said carriage through a predetermined stroke over said conveyor from a predetermined starting position, and in a return path back to said starting position said carriage including a rotatable member provided with an arcuate blanket portion extending less than 180 degrees around said cylinder rolling against the surface to be printed during travel of the carriage from said position, means to rotate said member as an incident of its reciprocation always in the same direction and effecting the rotation thereof at a sufficiently higher rate in the return travel of the carriage than in said printing travel to place the blanket portion in the same orientation as in said starting position at the end of said return travel, said carriage also including at least one form roll tangent with the path of said arcuate portion, means to deliver ink to said form roll, and a drive for said form roll and said ink delivery means connected to said rotatable member, said blanket portion in said return travel being out of the path of the surfaces and being re-inked by rolling engagement with said form roll, said member rotating means effecting said printing travel during a dwell with said blanket portion in contact with said surface.

15. The rotary printer of claim 14 in which the printer includes supporting structure, means connecting the carriage to the structure laterally of the conveyor for movement relative thereto through the predetermined stroke and the member rotating means includes gear means rotatable with the rotatable member of the carriage, said means connected to the structure and extending lengthwise of the path of the carriage and shiftable means to effect said different rates of rotation.
